[57] CLAIM

The ornamental design for a canted cordless telephone base unit, as shown and described.

DESCRIPTION

FIG. 1 is a top perspective view of a canted cordless telephone base unit showing our new design;

FIG. 2 is a top plan view of the canted cordless telephone base unit of FIG. 1;

FIG. 3 is a bottom plan view of the canted cordless telephone base unit of FIG. 1;

FIG. 4 is a left side elevation view of the canted cordless telephone base unit of FIG. 1;

FIG. 5 is a right side elevation plan view of the canted cordless telephone base unit of FIG. 1;

FIG. 6 is a front elevation view of the canted cordless telephone base unit of FIG. 1; and,

FIG. 7 is a rear elevation view of the canted cordless telephone base unit of FIG. 1.

The broken line showing of a handset in FIG. 1 is for illustrative purposes only and forms no part of the claimed design. The full rectangle of a circular apertures at the top rear right has been partially shown in FIGS. 1, 2, and 6 for convenience of illustration.
